UNITED STATES PATENT OFFICE.

CARL CORNWELL, OF OAKLAND, CALIFORNIA.

BIFUEL SYSTEM FOR GAS ENGINES.

Application filed May 13, 1925. Serial No. 29,909.

This invention relates to a bi-fuel system for gas engines, particularly for the utilization of the heavy fuel oils, I am aware that engines for using a light volatile fuel oil as gasoline for starting and a heavier running fuel oil, such as kerosene, after the engine has become warmed up, are not new but have been in use for a considerable period of time. My invention does not, therefore, relate to this idea broadly but to certain improvement therein. It is the general object of my invention to provide an improved bi-fuel system for gas engines of this type.

In this description the term "gas engine" is to be taken in its common meaning as describing an internal combustion engine designed for the use of volatile fuels.

The difference in the heat of vaporization of different-weight fuel oils requires apparatus for handling and vaporizing these oils independently and delivering the oil vapors independently to the gas intake port of the engine. Gasoline, being more volatile than heavier fuel oil, vaporizes at a much lower temperature, gasoline ordinarily vaporizing at atmospheric temperature whereas heavier fuel oil requires a heating thereof to a higher temperature. My invention, therefore, contemplates two independent carburetors for vaporizing two different-weight fuel oils, means for providing heated air of the proper vaporizing temperature to the carburetor using the heavier oil and independent manifolds for independently conducting these different temperatured oil vapors to the gas intake port of the engine. It is an object of my invention to provide an improved bi-fuel system for gas engines embodying these features.

It is a further object of my invention to provide in combination with the apparatus just defined a thermostatically controlled valve by which heated air of the proper temperature is automatically supplied to the heavier oil carburetor which valve control is simpler, and more accurate and efficient than such controlling devices heretofore known.

In the accompanying drawing I have shown certain specific embodiments of my invention, but it will be understood that the invention can be otherwise embodied and that the drawing is not to be construed as defining or limiting the scope of the invention.

This invention relates to a bi-fuel system for gas engines, particularly for the utilization of the heavy fuel oils, I am aware that engines for using a light volatile fuel oil as gasoline for starting and a heavier running fuel oil, such as kerosene, after the engine has become warmed up, are not new but have been in use for a considerable period of time. My invention does not, therefore, relate to this idea broadly but to certain improvement therein. It is the general object of my invention to provide an improved bi-fuel system for gas engines of this type.

Referring to the figures of the drawing, Fig. 1 is an elevation partially in section of a gas engine embodying the improved features of my invention;

Fig. 2 is an enlarged longitudinal sectional view of the thermostatic air controlling mechanism shown in Fig. 1.

In the drawing, 1 indicates an internal combustion engine having a crank shaft 2, a piston 3, a gas intake port 4, and an exhaust port 5 leading outwardly through an exhaust pipe 6.

Two carburetors 7 and 8 are mounted adjacent to the engine and connect to the intake port 4 by independent manifolds 9 and 10. As the operating temperature of light and heavy oils vary greatly it has been found necessary to provide two separate manifolds insulated from each other by an air space or other insulating material.

I have illustrated the carburetor 7 and its manifold 9 as smaller than the carburetor 8 and its manifold 10 since ordinarily the carburetor 7 uses a light fuel as gasoline only for starting and warming up the engine. Fuel is supplied to the carburetors 7 and 8 from pipes 11 and 12 and the flow of vaporized fuel therefrom is controlled by throttle valves 13 and 14. The carburetor 7 is also provided with an auxiliary valve 15 for admitting air thereto in the manner hereinafter described.

Heated air is supplied to the heavier oil carburetor 8 from a heater 16 surrounding exhaust pipe 6. A tube 17 connects this heater with the carburetor. A portion 18 of this tube as seen in detail in Fig. 2 is provided with a thermostatically controlled valve or gate 19 for automatically admitting cool air thereto when excessive heat therein requires. As illustrated, this valve 19 is pivoted to the tube at 20 and normally closes the opening 21 into the tube. The valve controlling element comprises two bars of metal 22 and 23, having different coefficients of expansion, riveted together and rigidly mounted on studs 24 centrally within the tube. The free end of the bars is connected to the valve by a pivoted bolt 25 and adjusting nuts 26.

In Figure 2 the bar and valve are shown

in full lines in the normal position; that is, when the air in the pipe 18 is unheated. Different grades of fuel require the vaporizing air to be heated to different temperatures and the adjusting nuts 26 provide means for adjusting the mechanism to open the valve the proper amount and permit cool air to enter when the air within the pipe reaches an excessive temperature. The bar 22, which 10 may be of an aluminum or copper alloy, has a greater coefficient of expansion than the bar 23, which may be of iron, and therefore upon excessive heating the double bar will bend to the position indicated in dotted lines 15 in Fig. 2 and open the valve, thereby exposing the thermostat to the resulting temperature of the two air streams and thus maintaining the desired temperature to the oil carburetor.

20 The operation of my improved system as illustrated is substantially as follows: In starting the engine, gasoline and air are admitted to the carburetor 7 in the usual manner. When the engine starts, the air valve 15 is partially closed in a manner to give an over-rich mixture of gasoline vapor. The valve 14 of the carburetor 8 is then slightly opened, thus permitting a flow of air to be drawn from the heater 16 through the carburetor, tube, and manifold. In this manner the engine exhaust operates to quickly heat the carburetor 8 and its parts to the vaporizing temperature. No fuel is admitted to the carburetor 8 until the heated air passing 35 therethrough has warmed the carburetor and its parts sufficiently to insure the vaporization of the heavy fuel.

When the carburetor 8 and its parts become sufficiently heated, fuel oil is admitted 40 to the carburetor from the pipe 12 and the engine is permitted to operate for a short time on both gasoline and oil. When load is applied to the engine, the exhaust heat increases the temperature of the air in the 45 pipe 17 and the gasoline is then entirely cut off, permitting the engine to run on oil alone. When the gasoline supply to the carburetor 7 is shut off the valve 15 thereof can be opened if desired to supply additional air 50 to the oil vapor through the manifold 9.

The use of the independent manifolds and the cooperating mechanism as illustrated and described provides for fully warming up the oil carburetor and its manifold to the oil 55 vaporizing temperature while starting the engine on gasoline. It will be understood that the gasoline vapor, being of a lower temperature, would considerably interfere with this warming-up operation were such 60 gasoline vapor to pass through the oil manifold 10. When the engine is fully operating on oil the thermostatic valve will automatically control the temperature of the air supplied to the oil carburetor as will be understood.

It is desirable in practice that the engine be able to operate at part load, this necessitating low compression in the cylinders. If the thermostat is set so as to provide the necessary heat to give a clean burning gas at 70 low compression, the gas vapor is liable to pre-ignite when the throttle is opened wide and the engine is operated on full compression. By using the auxiliary air valve 15 a supply of cold air can be admitted to the 75 heated vapor coming from the carburetor 8, thereby cooling the same below the point of ignition and supplying additional oxygen for the complete combustion of the vapor. This follows the well known principle that 80 an engine at full compression will burn a leaner mixture than at low compression. This arrangement also provides a means of operating continuously at variable loads 85 tailing less than full compression.

The apparatus when constructed in accordance with my improved system will operate to start the engine on gasoline in a minimum of time and with a minimum consumption of fuel. During this time the oil 90 carburetor and its associated parts are heated to the proper temperature in a manner permitting the exclusive use of the cheaper oil fuel within the period of a very few minutes necessary to heat up the engine. Thereafter 95 the thermostatically controlled valve operates to automatically supply the carburetor 8 with heated air of the proper vaporizing temperature whereby the engine operates on the heavier fuel without further attention or 100 consideration. If it is desired to use the engine on load instantly or before the carburetor 8 has become heated, a larger gasoline carburetor is provided, the operation thereof being the same but with a larger expenditure of gasoline.

No special carburetor is specified, as several standard makes of carburetor have been found suitable for both oil and gasoline as used in this apparatus. Nor is any special 110 type of retort for heating the intake air necessary, as such retorts or stoves may be varied greatly to suit the needs of different installations. I have found by actual use that with this apparatus it is possible to 115 operate a gas or gasoline engine on cheap and heavy oils with little or no carbon deposit and almost perfect combustion of the heavy oil.

Having thus described my invention, what 120 I claim and desire to secure by Letters Patent is:

An internal combustion engine having an intake port and an exhaust port, a light fuel carburetor, a manifold from the carburetor 125 to the intake port, a heavy fuel carburetor, a manifold therefrom to the intake port, said manifolds joining each other substantially at right angles where they connect with the intake port, means providing a conduit for 130

conducting air heated from the exhaust gases into the second carburetor, thermostatic-controlled means for admitting cool air to the conduit to maintain a constant temperature, 5 and a relatively large manually-controlled air valve cooperating with the first carburetor and adapted to admit outside at-

mospheric air thereinto, this air being conducted through the first manifold into the intake port wherein it mixes with the heavy fuel vapor from the second carburetor to form an explosive mixture of the proper proportions.

CARL CORNWELL.
